UNITED STATES PATENT OFFICE

FREDERICK A. GREIS, OF LYNBROOK, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed October 3, 1928. Serial No. 309,947.

This invention relates to typewriting machines equipped for typing index-cards and other work-pieces, upon which it is desired to type an address at the extreme top edge. It is usual to insert the card at the front of the platen and pass it down, bottom first, until the top border has descended to the printing line of the machine. Sometimes the platen is rotated backwardly, for carrying the card down. In some cases a long card is inserted head-first at the back of the platen, and the latter is rotated forwardly to bring the card around under the platen and up in front until the top border of the card reaches printing position. In either case there is necessary considerable manipulation of the card or the platen or both; and much time-consuming adjustment is found necessary. Sometimes gages are used for the bottom edge of the card, and sometimes for the top edge, but bottom gages are often unsatisfactory, partly because they do not answer for different sizes of cards; and top-edge gages require undue attention to be given to the manipulation of the cards.

Moreover the card has to curve around the platen, and it is found that the top edge of the card is not properly supported against the platen. The card being stiff tends (when curved) to bulge away at its top edge from the platen, and it is impracticable to hold the top of the card against the platen by means of any device that engages the top edge of the card, because the types would strike said holding device, and hence the address could not be written at the very top edge of the card. This trouble is accentuated when the entire body of the card is curved around the platen in order to bring its top edge to printing position. The difficulty is especially noticed in typewriting machines of the portable class, in which the diameter of the platen is small, and the card must be bent more. Moreover considerable time is lost in manipulating any devices that are used for holding the top border of the card firmly against the platen. The card cannot be permitted to bulge from the platen, because the type-impressions will be blurred and unsatisfac-

tory, and the machine rendered unduly noisy.

The object of the present invention is to overcome these and other objections.

To do this the card, whether long or short, is inserted head-first downward at the front of the platen, until the head edge thereof is at the printing line, so that the type-impressions will fall immediately upon or along the edge portion, and as close to the actual edge as may be desired. The head edge of the card is set down to a gage. After the line is typed, the card is raised and withdrawn. This is simply an inserting and withdrawing operation, requiring no adjustment or truing or manipulation of either card or platen, and great saving of time and labor is effected.

In order to render this card-typing operation possible, the types are placed up-side-down upon the usual type-bars, and hence print up-side-down upon the card. When the latter is removed from the machine and turned around to proper position, the line will be found properly and legibly typed thereon.

In order to make the use of inverted types feasible, provision is made for letter-feeding the typewriter-carriage in the reverse of the usual direction, that is, from left to right in ordinary round-platen machines. This reverse feeding compensates for or rectifies the inversion of the types in the machine, and the inversion of the types rectifies the inversion of the card, and hence by manipulation of the typewriter-keys, in the ordinary manner, the address is properly typed upon the top edge of the card, which is brought directly to the printing line by a simple insertion of the card, and is withdrawn by a simple stroke of the hand. A suitable gage is provided in the machine for the top edge of the inverted card, and there are also preferably provided suitable side gages for the card.

The card at the printing operation can be entirely or almost entirely in flat or unsprung condition, that is to say, it needs to be bent very little if at all around the platen. At most, it needs to be bent only sufficiently

to enable the capital-types to clear the card, to avoid offsetting of the capital-types thereon, in case both capital and lower-case types are used. Inasmuch as the card is not bent 5 around the platen to any substantial extent, it does not tend substantially to bulge away from the platen, and hence it may be straight and therefore firmly backed by the platen at all points in the line of typing. 10 This produces satisfactory work, and minimizes the noise. If types are used that have only capital-letters thereon, then all liability of offsetting of the types is avoided. Moreover the card may be inserted in the 15 machine in perfectly flat and straight condition with no tendency in its middle portion to bow away from the platen.

Since each type-bar preferably carries upper and lower case types, and since the type-blocks are in inverted positions on the type-bars, it is preferably provided that the platen shall normally occupy its upper position, so that the lower-case types will normally print. Upon depression of the case-shift key, the platen is lowered to enable 25 the capital-types to print.

The reverse letter-feeding of the carriage is effected by inserting a reverse-gear train between the usual carriage-rack-pinion and 30 the usual escapement-wheel.

The carriage may be propelled from left to right by the usual carriage spring-barrel, with the aid of a movement-reversing pulley over which the spring-strap is carried.

35 There is illustrated a four-row Underwood portable typewriting machine, although the invention may be applied to a great variety of machines.

Other features and advantages will hereinafter appear.

In the accompanying drawings,

Figure 1 is a front elevation of the carriage of a four-row portable machine, showing a card inserted therein in typing position, and also showing the means for letter-feeding the carriage from left to right.

Figure 2 is an enlarged diagram, showing the inverted arrangement of the type-blocks upon the tips of the swinging type-bars.

30 Figure 3 is a plan, showing features seen in Figure 1.

Figure 4 is a perspective, showing an inverted card inserted head-first in the machine preparatory to writing with inverted 55 types upon the top edge. This view shows top and side edge gages for the card.

Figure 5 is a sectional elevation taken from front to rear through the typewriting machine.

30 Type-keys 10 are depressed to operate levers 11, which by means of bell-crank 12 and links 13 swing type-bars 14 upwardly about pivots 15, so that type-blocks 16 on the tips of the bars may strike rearwardly 130 against the front of a platen 17.

The platen is mounted by an axle 18 in a carriage 19, running upon front ball-bearings 20 and rear roll 21, and propelled by a spring-barrel 22, from which extends a strap 23 running around a pulley 24 journaled at 25 upon a support 26. The strap runs 70 around the pulley and then back at 27, and is connected at 28 to the left-hand end of the carriage 19, thereby propelling the carriage from left to right.

At each stroke of a key-lever, a universal bar 29 is depressed, and an arm 30, connected thereto, vibrates forwardly and swings a dog-rocker 31, whose dogs 32 work in and out of notches 33 of a toothed escapement-wheel 34, pivoted at its usual place in an Underwood machine upon shaft 35. Also upon the shaft is a pinion 36, forming part of a reverse gear-train. Pinion 36 meshes with pinion 37, which is fixed upon a shaft 38, the latter carrying a pinion 39 in mesh with a rack 40 provided upon the carriage. This rack, with the carriage, moves from left to right, when permitted by feed-dogs 32, under control of universal bar 29 and 85 keys 10.

The type-blocks 16 are in inverted positions upon the type-bars 14 as at Figure 2, and therefore print upside down upon a work-card 41, Figure 1.

Where capital-types 16^a and lower-case types 16^b are employed upon the type-bars, the platen may usually occupy its upper position as at 17^a, seen in dotted lines in Figure 5. When it is desired to print a capital-letter, a shift-key 42 may be depressed, thereby depressing a lever 43, whose rear end 44 rises, thereby vibrating a sub-lever 45, whose rear end depresses an arm 46 forming part of a platen-shift frame, 105 other usual portions of said frame being indicated at 47, 48 and 49.

The platen-carriage feeds to and fro upon said frame, and is guided thereby, and also shifted up and down thereby. As long 110 as the shift-key 42 is held depressed, the capital-letters 16^a will print. This key may be held down mechanically by means of the usual locking key 50, Figure 5.

From the foregoing, it will be seen that 115 it is only necessary to set a card down in front of the platen as far as it will go, and then operate the type-keys.

Any suitable gaging means may be provided for the leading or head edge of the 120 card, and, for purpose of illustration, there is shown a card-holder which is self-clamping upon the platen, although other types of card-holders may be used. In some cases the card may be held upon the platen by 125 the aid of the usual front scale or "wing-scale", not shown, which remains stationary while the carriage travels, and which may extend up above the printing line on the card, without preventing the typing of the 130

card, and with the effect of holding the card even more firmly against the platen at the point of typing.

The illustrated card-holder is formed of springy sheet-metal and includes a cross-bar or body-member 51, upon the ends of which are forms or clasps 52, which encircle the platen and may be formed integral with the body or cross-bar 51. These clasps 52 are springy, and curve more than half-way around the platen, thus rendering the card-holder self-clasping and self-retaining upon the platen.

The platen does not need to be rotated if only a single line is to be written on the card. If it is desired to write a few lines, the usual line-spacing mechanism indicated at 53, 64, may be employed. Wheel 53 is controlled by the usual detent 54 and other devices. The platen may be rotated backwardly by the usual knob 55, for effecting such line-spacing as may be required; and the card-holder 51, 52 will be carried around by the platen.

A gage for the printed edge of the inverted card may include two shoulders 56 extending towards each other from the platen-clasping portions 52 of the card-holder. These shoulders form edges or abutments of sufficient thickness to serve as a gage down against which the card may be thrust.

The card may be held against the platen with sufficient firmness by means of yieldable fingers 57 secured upon the card-holder, one at each side of the card. These fingers engage the side edges of the card, and are spaced sufficiently apart to permit of writing upon the card. The fingers may have a forward flare at the top, as at 58, to make an opening to facilitate the introduction of the card between the guide-fingers and the platen.

There may be also formed side-edge gages 59 for the card, Figure 4, so that the card may be inserted and mechanically located in exact writing position without loss of time. These side-edge gages may be more apart than the guiding fingers 57, but not so far apart as the clasps 52, and they may be formed by cutting the clasps to the required shape. In so doing, an oblique guiding portion 60 may be provided to lead the card down between the side gages 59.

If only capital-letters are to be employed in the machine, the frame 46, 47, 48 may be fixed permanently in its uppermost position. Preferably, however, said frame and the carriage are retained in said uppermost position by a spring 61, which is coiled about a transverse rock-shaft 62, usually forming part of the carriage-shift frame in portable typewriters.

For each line typed upon a card, it is necessary to return the carriage to the left,

preparatory to beginning the typing of a new line; and this leftward movement may be effected by means of a finger-piece or finger-hold 63 fixed at the left-hand end of the carriage.

A carriage-returning line-spacing handle is commonly in use in the well-known three-row Underwood portable typewriting machine, as indicated diagrammatically by dotted lines at 64, Figure 1. It is placed to the left of said finger-pieces 63, in position to enable them to be pinched toward each other, thereby affording a grip for the purpose of controlling the movements of the carriage. Handle 64 is not used unless it is desired to line-space the card. It may line-space the platen backwardly, the teeth of wheel 53 being formed reversely for this purpose, and any suitable drive-pawl being employed between the carriage-returning handle 64 and the reversed ratched-wheel 53.

Variations may be resorted to within the scope of the invention, and portions of the improvements may be used without others.

Having thus described my invention, I claim:

1. In a typewriting machine, the combination with a platen, a platen-carriage and a system of inverted types to strike upon the platen, of means for letter-feeding the carriage in reverse direction, and a gage on said carriage in front of the platen to gage the head edge of an inverted card in printing position.

2. In a typewriting machine, the combination with a platen, a platen-carriage and a system of inverted types to strike upon the platen, of means for letter-feeding the carriage in reverse direction, and a gage on said carriage in front of the platen to gage the head edge of an inverted card in printing position, said gage being placed at the printing line to permit the impressions to be made upon the extreme edge of the card.

3. In a typewriting machine, the combination with a platen, a platen-carriage and a system of inverted types to strike upon the platen, of means for letter-feeding the carriage in reverse direction, a gage on said carriage in front of the platen to gage the head edge of an inverted card in printing position, and card-guiding means extending up from the printing line and open at the top to permit the card to be thrust down head first between the platen and said guiding means to said gage.

4. In a typewriting machine, the combination with a platen, a platen-carriage and a system of inverted types to strike upon the platen, of means for letter-feeding the carriage in reverse direction, a gage on said carriage in front of the platen to gage the head edge of an inverted card in printing position, said gage being placed at the printing line to permit the impressions to be made upon

the extreme edge of the card, and side-edge gages for said card.

5. In a typewriting machine, the combination with a platen, a platen-carriage and a system of inverted types to strike upon the platen, of means for letter-feeding the carriage in reverse direction, a gage on said carriage in front of the platen to gage the head edge of an inverted card in printing position, said gage being placed at the printing line to permit the impressions to be made upon the extreme edge of the card, side-edge gages for said card, and flaring means directing the card to said side-edge gages.

15 6. In a typewriting machine, the combination with a platen, a platen-carriage and a system of inverted types to strike upon the platen, of means for letter-feeding the carriage in reverse direction, and a gage on said carriage in front of the platen to gage the head edge of an inverted card in printing position, self-clasping means being mounted upon said platen and having said gage thereon.

25 7. In a typewriting machine, the combination with a platen, a platen-carriage and a system of inverted types to strike upon the platen, of means for letter-feeding the carriage in reverse direction, and a leading-edge gage in front of the platen to gage the head edge of a card in printing position, and a side edge gage for the card.

8. In a typewriting machine, the combination with a platen, a platen-carriage and a system of inverted types to strike upon the platen, of means for letter-feeding the carriage in reverse direction, and a leading-edge gage in front of the platen to gage the head edge of a card in printing position, said card-gage in the form of a body having on its ends curved horns or clasps to clasp the platen, and also having an edge-portion constituting said leading-edge gage.

45 9. In a typewriting machine, the combination with a platen, a platen-carriage and a system of inverted types to strike upon the platen, of means for letter-feeding the carriage in reverse direction, and a leading-edge gage in front of the platen to gage the head edge of a card in printing position, said card-gage in the form of a body having on its ends curved horns or clasps to clasp the platen, and also having an edge-portion constituting said leading-edge gage, and also having a side-portion constituting a side-edge gage.

10. In a typewriting machine, the combination with a platen, a platen-carriage and a system of inverted types to strike upon the platen, of means for letter-feeding the carriage in reverse direction, a gage on said carriage in front of the platen to gage the head edge of an inverted card in printing position, card-guiding means extending up from the printing line and open at the top

to permit the card to be thrust down, head-first, between the platen and said guiding means to said gage, and yielding fingers upon said card-guide to hold the card by its side borders.

70 11. In a typewriting machine, the combination with a platen, a platen-carriage and a system of inverted types to strike upon the platen, of means for letter-feeding the carriage in reverse direction, a gage on said carriage in front of the platen to gage the head edge of an inverted card in printing position, card-guiding means extending up from the printing line and open at the top to permit the card to be thrust down, head first, between the platen and said guiding means to said gage, and yielding fingers upon said card-guide to hold the card by its side borders, said fingers each having a forward flare at its top.
